By John K. Hendry, Atty.

UNITED STATES PATENT OFFICE.

DUNCAN NEIL MILLER, OF HAMILTON, CANADA.

RAILWAY-CAR SANDER.

SPECIFICATION forming part of Letters Patent No. 710,489, dated October 7, 1902.

Application filed April 10, 1902. Serial No. 102,207. (No model.)

To all whom it may concern:

Be it known that I, DUNCAN NEIL MILLER, a citizen of Canada, residing at Hamilton, in the county of Wentworth and Province of Ontario, Canada, have invented certain new and useful Improvements in Railway-Car Sanders; and I do hereby declare the following to be a full, clear, and exact description of the invention, such as will enable others skilled in the art to which it appertains to make and use the same.

My invention relates to railway-car sanders, more especially to street-railway cars; and it consists of a hopper to contain sand and designed to be located under the seat of a car and resting on the floor. The lower part of the hopper has a horizontal cylinder communicating with the hopper and a varying-pitch worm in the cylinder capable of being revolved by the motorman of the car by means of mechanism connected to the worm and extended to a hand-wheel in proximity to the motorman. A pipe or tube communicates from the cylinder to a position above one of the ground-rails and in front of one of the forward wheels to allow sand to fall on the rail when operated.

The objects of my invention are, first, to provide a railway-car sander which shall operate in a most satisfactory manner and under the control of the motorman; second, to provide a railway-car sander which shall be hidden from view; third, to provide a railway-car sander which shall be capable of discharging sand when the same is damp or dry or contains small stones, and, fourth, to afford facilities for entering the discharging end of the cylinder without taking out the end thereof. I attain these objects by the mechanism illustrated in the accompanying drawings, in which—

Figure 1 is a sectional elevation of the sanding device shown in position on the floor of a street-railway car, also the position of the sander to one of the front wheels of the car. Fig. 2 is an end elevation of the front end of the sander, showing the sprocket driving-wheels and located under the hinged seat of a car; and Fig. 3 is an enlarged sectional end elevation of the discharging end of the horizontal cylinder of the hopper, showing the end sliding cover of the cylinder.

Similar characters refer to similar parts throughout the several views.

In the drawings the sand-hopper is indicated by A and its lower horizontal cylinder by B. The cylinder is supported by base-brackets C, which are secured to the floor D of the car. The cylinder extends about one-third of its length past each end of the feed part of the hopper. The horizontal cylinder-shaft E has a worm or screw F inside the cylinder. The worm varies in the pitch—that is, a larger pitch at the sand-discharge end of the cylinder than the forward end of the cylinder—continuing in gradual reduction of the pitch to its forward end. The gradual increase of the pitch of the worm from the forward end to the discharge end of the worm adds to its efficiency in passing through the sand and in forcing the sand gradually to the discharging end. This feature is important. The bearings H are secured to the floor D and support the shaft E. The hangers K are secured to the underside of the floor D and support the horizontal shaft M. N represents adjustable collars on the same shaft. The discharging end of the cylinder is provided with a cover 2, which is capable of sliding in the guides 3 to open said cylinder for various purposes—for instance, especially to remove a large stone or other foreign matter.

Above the cylinder B is a horizontal shaft P in bearings 4 of the hopper. This shaft P has a number of projecting pins or teeth 5, which project out from the shaft P in the hopper to disturb and agitate the sand in the hopper that the sand, more especially damp sand, may flow freely from the hopper to the cylinder when the shafts P and E are revolved.

R is the discharge-pipe of the cylinder, and S is a flexible continuation of said discharge-pipe located immediately in front of the forward car-wheel W.

The forward end of the worm-shaft E has sprocket-wheels T and U secured thereto, and the upper shaft P has a sprocket-wheel V secured thereto. The sprocket V is driven by the sprocket U by means of the chain 6. A sprocket-wheel Y is secured to the shaft M and drives the sprocket T by means of the chain 7.

The vertical shaft 8 at the forward end of the car is supported by the bushing 9 of the

floor D and the collar 10 of the shaft. Other upper steadyng means may be employed for this shaft 8.

12 is a hand-wheel on the upper end of the shaft 8 to revolve the shaft. The lower end of the shaft 8 has a bevel-wheel 13 secured thereto which gears into the bevel-wheel 14, secured on the forward end of the shaft M.

The hopper, with its cylinder, together with its immediate mechanism above the floor, is located under a forward seat 16 of a car. The seat 16 is hinged at 17 to the framework 18 of the car and may be opened, as shown in broken lines in Fig. 2 of the drawings, to obtain access to the hopper for filling and other purposes.

The operation of the invention is as follows: When the hopper has sufficient sand, the hand-wheel 12 is revolved, as indicated by arrow. 20 The shaft 8 revolves the horizontal shaft M by means of the gears 13 and 14. The shaft M revolves the horizontal shaft E, together with its worm F, by means of the sprockets Y and T with their chain 7. Consequently 25 the upper shaft P, together with its teeth 5, is revolved at the same time by means of the sprockets U and V with their connecting-chain 6. The sand is then discharged from the cylinder and through the discharge-pipes 30 R and S onto the car-track rail.

Various changes in the form, proportion, and minor details of this invention may be resorted to without departing from the spirit and scope thereof.

35 Hence what I claim as my invention, and desire to secure by Letters Patent, is—

1. In a railway-car sander, a hopper with lower horizontal cylinder communicating with

the hopper and extending beyond the feeding ends of the hopper, a sliding cover on the discharging end of the cylinder, a horizontal shaft extending through the cylinder, bearings secured to the car-floor and under the car-seat to support the shaft, a lower discharge-pipe communicating with the rear 40 part of the cylinder, a worm as described on the shaft and extending from the discharge-outlet to near the forward end of the cylinder, a sprocket-wheel secured on the forward end of the shaft and means for revolving said 50 sprocket, substantially as described.

2. In a railway-car sander, a hopper, a lower horizontal cylinder communicating with the hopper and extending past the feeding ends thereof, a horizontal shaft extending through 55 the cylinder, bearings secured to the car-floor and under a seat, for said shaft, a discharge-pipe communicating with the rear extended part of the cylinder, a worm of gradual varying pitch on the shaft and extending from the 60 discharge-outlet to near the forward end of the cylinder, a sprocket-wheel secured on the shaft at the forward end thereof, a horizontal hopper-shaft extending through the hopper, teeth projecting from the part of said 65 shaft in the hopper, a sprocket-wheel on the hopper-shaft, a chain connecting said sprockets and means for revolving the sprocket on the worm-shaft, substantially as described.

In testimony whereof I affix my signature 70 in presence of two witnesses.

DUNCAN NEIL MILLER.
